LET-OFF

Oscar V. Payne, Leicester, Mass., assignor to
Crompton & Knowles Loom Works, Worcester,
Mass., a corporation of Massachusetts

Application May 8, 1934, Serial No. 724,527

6 Claims. (Cl. 139—109)

This invention relates to improvements in let-offs for looms and it is the general object of the invention to provide means for increasing the rate of feed of the warp threads.

5 In my prior Patent No. 1,803,143 there is shown a let-off which has gone into extensive use and having in its construction a weight which tensions the warp threads through a worm and worm wheel. As the warp is consumed a support 10 for the weight is moved forwardly together with the worm, worm wheel and worm actuating plunger, and when a predetermined point is reached a regularly acting feed arm or wing pushes the plunger. The plunger acts to rotate 15 the worm in such a direction as to turn the worm wheel and weight support backwardly. By this means the weight constantly stresses the warp threads without being wound up on a large drum or rising through a large distance and continuous forward movement of the warp is accompanied by an alternate forward and backward movement of the worm and weight support.

20 The plunger shown in my prior patent is moved inwardly by the feed arm every beat of the loom, but I have found in certain fabrics which use very coarse weft that the advance of the warp thread is so rapid as to require more frequent feeding than can be accomplished by the motion shown in said patent. It is accordingly an 25 important object of my present invention to provide means for giving the plunger more frequent actuating motions and this result I accomplish as set forth specifically hereinafter by means of a toggle type of motion in which each 30 backward and each forward motion of the lay effects a feeding motion of the plunger. A motion of this type can be readily adapted to a let-off shown in the previously mentioned patent, but it is not necessarily limited to motions as 35 shown therein.

40 With these and other objects in view which will appear as the description proceeds, my invention resides in the combination and arrangement of parts hereinafter described and set forth 45 in the claims.

In the accompanying drawings, wherein a convenient embodiment of my invention is set forth,

Fig. 1 is a side elevation of a loom having my 50 invention applied thereto,

Fig. 2 is a detailed top plan view of one rear side of the loom taken in the direction of arrow 2, Fig. 1,

Fig. 3 is a detailed view partly in section of 55 part of the structure shown in Fig. 1,

Fig. 4 is a horizontal section on line 4—4 of Fig. 3, and

Figs. 5, 6 and 7 are diagrammatic views showing the parts in different positions.

Referring to the drawings, the loom frame 10 is provided at the rear thereof with a warp beam B supplying warp W. The lay L is driven back and forth in the usual manner by crank shaft 15. The gudgeons 20 of the warp beam pass through vertically adjustable supports 44, one 10 of which is shown in Figs. 1 and 2, bolts 45 passing through the loom frame and the supports 44 to afford adjustment.

A worm wheel 36 is secured to the warp beam and is rotatable with the latter about the axis 15 thereof, and meshes with a worm 50 keyed to a shaft 52. This shaft has rotatable thereon a collar 64 which has a ratchet tooth connection 66 with a second collar 60 keyed to the shaft. The collar 64 is provided with gear teeth 78 which 20 mesh with a rack 79 formed as a part of a plunger 76. The latter reciprocates in a housing 30 which forms part of the support for the worm wheel 36, and a light spring 80 tends normally to hold the plunger outwardly. A stop 11 as shown in Fig. 4 limits outward movement under action of the spring.

When the plunger 76 is moved inwardly it turns the collar 64 in a clockwise direction, as viewed in Fig. 4, to turn the collar 60 through the ratchet 30 connection 66, thus rotating the worm 50. The latter in turn gives a partial backward or reverse rotation to the worm wheel so that a segment 62 which supports a weighted cord C moves in a left hand direction as viewed in Fig. 3.

As shown more particularly in Fig. 2 a feed arm or wing 84 is pivoted at 85 to the support 44 and is adapted to rock in a fixed plane. When the segment 62 and the worm, together with the worm wheel and the plunger 76, are in their extreme left hand position the plunger is out of the path of the wing 84 and the latter vibrates idly. As weaving continues the warp W moves forwardly and turns the beam and the plunger in a right hand direction as viewed in Figs. 1 45 and 3, ultimately bringing the plunger into the range of action of the wing 84, after which reverse feeding of the worm as already described will take place. The matter thus far described may be substantially the same as shown in my 50 previously mentioned patent and of itself forms no part of my present invention.

In carrying my invention into effect I provide means for giving the plunger 76 an increased number of reciprocations for each beat of the 55

loom. The mechanism for accomplishing this result is set forth in Figs. 2 and 4, where it will be seen that the wing or feed arm 84 has pivoted thereto a link 90 which in turn is pivoted at 91 to a second link 92. The latter is pivoted as at 93 to a fixed extension 94 of the support 44. A rod 88 is pivoted as at 89 at its rear end to the link 92 and at its forward end is pivoted to a lever 74 which in turn is connected to a second rod 75 attached pivotally at 95 to the lay sword 96. In my prior patent I have shown an eccentric on the crank shaft to oscillate the rod 88, but I find it convenient to effect this reciprocation of the actuator rod by a direct connection 15 with the lay as set forth more particularly in Fig. 1.

The mode of operation is set forth diagrammatically in Figs. 5, 6 and 7. As shown in Fig. 5, when the lay is in its rearmost position rod 88 will move the two links in such a position as to place the wing 84 away from the plunger 76. As the lay advances, however, to the position indicated in Fig. 6, the rod 88 will pull the links until they are straightened, thereby swinging the 25 wing or feed arm toward the plunger and moving the same to give a feeding motion to the worm 50. As the lay continues to its extreme forward position as indicated in Fig. 7 the links will move forwardly in a way to retract the wing. As the 30 lay starts backwardly the parts will again assume the position shown in Fig. 6 with the links aligned and the wing giving the plunger another feeding action. When the lay reaches its extreme rearward position the links will be as indicated in 35 Fig. 5.

It will be seen by these motions that each sweep of the lay either backwardly or forwardly will move the wing 84 into operative relation with the plunger 76 to feed the warp. In other words, for each complete pick or cycle of the loom including a forward and backward movement of the lay there will be two feeding movements of the plunger. In this way the let-off is adapted for use with very coarse weft where the feeding 45 of the warp must be rapid.

From the foregoing it will be seen that I have provided a very simple means for increasing the speed at which warp can be fed with a let-off motion, the mechanism preferably employing 50 toggle members which give the feeding plunger 76 a working stroke twice for each beat of the loom.

Having thus described my invention it will be seen that changes and modifications may be made 55 therein by those skilled in the art without departing from the spirit and scope of the invention and I do not wish to be limited to the details herein disclosed, but what I claim is:

1. In a loom having a warp supply, a lay movable backwardly and forwardly therein, a let-off including a yielding element to control feeding of the warp supply, actuating means to cause relative movement of the element with respect to the warp supply, and means defining a toggle joint operatively connected to the lay to give said actuating means an operative movement

each time the lay passes between its extreme forward and extreme backward position.

2. In a loom having a warp supply, a lay movable backwardly and forwardly therein, a let-off to feed the warp supply, weighted means forming part of the let-off to tension and resist feeding of the warp and tending to move with the warp as the latter feeds forwardly, control means to effect a relative backward movement of the weighted means with respect to the warp, means defining a toggle joint, and mechanism to cause said toggle joint to give the control named means an operative movement relatively to the weighted means each time the lay reaches its mid position between front and extreme positions regardless of the direction of movement of the lay.

3. In a loom having a warp supply, a lay movable backwardly and forwardly therein, a let-off to feed the warp supply, weighted means forming part of the let-off to tension and resist feeding of the warp and tending to move with the warp as the latter feeds forwardly, control means to effect a relative backward movement of the weighted means with respect to the warp, a wing member to engage and actuate the control means, a pair of links constituting a toggle joint operatively connected to the wing member, and connections between one of the links and the lay to straighten said links and give the wing member an operative motion with respect to the means each time the lay moves between its front and back extreme positions.

4. In a loom, a lay movable back and forth, a warp beam, a worm wheel fixed thereto, a weighted casing pivotally mounted concentric with said worm wheel, a worm rotatably mounted in said casing and engaging said worm wheel, a toggle joint operated by the lay twice each time said lay has a back and forth motion to intermittently actuate said worm as the warp is unwound from said beam, said casing being relatively movable angularly in one direction by the unwinding movement of the warp beam, and said casing receiving a compensating relative angular movement in the opposite direction by the coaction of said worm and worm wheel, and a releasable clutch connection between said worm and said actuating means, whereby said worm may be released for manual actuation.

5. The combination in a loom as set forth in claim 4, in which a gear is mounted co-axial with said worm, a clutch connection is provided between said gear and said worm, and a rack operable by the toggle joint engages said gear, said rack being movable longitudinally in one direction by said toggle joint to rotate said worm and gear.

6. The combination in a loom as set forth in claim 4, in which a gear is mounted co-axial with said worm, a clutch connection is provided between said gear and said worm, and a rack operable by the toggle joint engages said gear, said rack being movable longitudinally in one direction by said toggle joint to rotate said gear and worm and being movable in the opposite direction by a spring.

OSCAR V. PAYNE.
